(57) **CLAIM**

We claim the ornamental design for a container for food, as shown and described.

DESCRIPTION

FIG. 1 is a top perspective view of the container for food according to a first embodiment of the present invention;

FIG. 2 is a right side view of the embodiment of FIG. 1.

FIG. 3 is a bottom perspective view of the embodiment of FIG. 1.

FIG. 4 is a top perspective view of the container for food according to a second embodiment of the present invention;

FIG. 5 is a top view of the embodiment of FIG. 4.

FIG. 6 is a bottom view of the embodiment of FIG. 4.

FIG. 7 is a bottom perspective view of the embodiment of FIG. 4.

FIG. 8 is a right side view of the embodiment of FIG. 4; and, FIG. 9 is a left side view of the embodiment of FIG. 4.

The left side view of the design of the embodiment of FIG. 1 is a mirror image of the right side view, so the left side view has been omitted.

In the drawings, the broken lines depict unclaimed subject matter only and form no part of the claimed design.
